United States Patent

Des. 237,927

Patented Dec. 9, 1975

237,927

BOOK HOLDER AND SUPPORT FOR TELEPHONE DIRECTORIES AND THE LIKE

Donald G. King, 241 Dickson Park Crescent,
Mississauga, Ontario, Canada

Filed May 6, 1974, Ser. No. 467,444

Term of patent 14 years

Int. Cl. D6—04

U.S. Cl. D6—114

FIG. 1

FIG. 2

FIG. 4

FIG. 3

FIG. 5

FIG. 1 is a front perspective view of a book holder and support for telephone directories and the like, showing my new design;

FIG. 2 is a rear perspective view thereof;

FIG. 3 is a front elevational view thereof;

FIG. 4 is a top plan view thereof; and

FIG. 5 is a bottom plan view thereof.

I claim:

The ornamental design for a book holder and support for telephone directories and the like, as shown.
